UNITED STATES PATENT OFFICE

JOHN B. BROWNING, OF CAMDEN, NEW JERSEY

RADIOTELEPHONOGRAPH

Original application filed June 26, 1922, Serial No. 570,906. Divided and this application filed February 25, 1927. Serial No. 170,794.

An object of this invention is to embody into a unitary system the most desirable reproducing characteristics of both the phonographic and radio arts.

Another object is to combine into a portable device, radio receiving and transmitting circuits, sound reproducing and recording means with or without a mechanical amplifier for audible sound waves.

10 A further object is to provide in such a device a radio antenna or pick-up so arranged in relation to the other elements that it may be directionally positioned with respect to the sound outlet of the cabinet without changing the position of any other element.

Further objects as well as details of construction and operation are hereinafter fully brought out in the following description 20 when read in conjunction with the accompanying drawing in which

Figure 1 is a vertical section of one embodiment of my invention, taken along line 1—1 of Figure 3.

25 Figure 2 is a horizontal section taken along line 2—2 of Figure 3.

Figure 3 is a side view partly in section.

Figure 4 is an enlarged plan view of the double goose neck carrying the mechanical 30 sound recorder or reproducer and the electrical receiver or transmitter.

Figure 5 is an enlarged side view of the elements shown in Figure 4.

In my preferred modification as shown in 35 the drawing my invention is housed within a table cabinet 50, which may be replaced by any other type of enclosure. The cabinet is provided with a plurality of resonance chambers as 52 and 56, positioned between 40 the walls of the cabinet and the walls of the mechanical amplifier. Each of the resonance chambers may be subdivided into smaller chambers 53, 54, 57 and 58, within each of which may be disposed various parts 45 of the phonograph and the radio set without materially affecting the resonance of the cabinet. Between the two chambers 52 and 56 and beneath the cover 60 is provided a central sound amplifying chamber 55 which 50 surrounds the inner amplifier 65 and 66.

The inner amplifier includes a hollow vibratory tapered portion 65, which is carried by a hollow non-vibratory connection 66, which communicates with a minor hollow tapered portion 4. A plurality of movable hollow tapered transversely extending portions 164 and 164^a are pivotally carried by the portion 4, and a plurality of hollow tapered portions 71 and 72 are carried by the connection 66 all of which, including 4 55 and its connections, lead to the common outlet of 65. The hollow tapered portion 4 and its connections are arranged to swing in a vertical and lateral plane above the turntable 7, and record 6, while 66 and its connections are arranged to swing in the same manner below the record. A substantially heavy portion 66^a is carried at the rear of 66 to counterbalance the weight of 4 and its connections. 60

70 The extending connections 164, 164^a, 71, 72 and 73 are arranged to communicate with the receivers 165, 166 or a loud speaker 168, either of which may have different tonal characteristics and be interchanged, the mechanical or electrical sound recorder or reproducer 5 and 162 are also interchangeable. 75

It will be noted that 4 and 65 with their connections form a continuously curving tapering sound amplifier of continuously increasing cross section avoiding all sharp turns, thus giving all the efficiency of a large cumbersome straight horn. Not only is this arrangement of a special advantage when used in connection with the phonograph, 80 but is also of a great advantage when used in cooperation with the radio set. 85

Arranged across one end of the chamber 55 are a plurality of deflectors 75 which may be adjusted to deflect the sound upward or downward and also arranged at the delivery openings of this chamber are doors 77, 78, 79 and 80 which may be adjusted to modify the quality of the reproduction at will on either side of the cabinet. 90 Doors 82, 82', 83 and 83' are also provided for the chambers 52 to 53, 54, 56, 57 and 58. 95

The dividing walls 90 and 91 arranged between the chambers 52 and 56 are semi-transparent or conductive to sound vibra- 100

tions, each of which may be provided with sound openings 96 through which sound may pass into the adjacent chambers and then into the atmosphere.

10 The panel or motor board 92 may be divided into a major portion 92 and two minor portions 92' and 92'', the minor portions being easily removed while the major portion may be hinged at 92^a or removable in a manner well known in the talking machine art.

15 The radio antenna shown in this modification, which may be varied, includes a square frame 85, with four cross pieces 86 one at each corner, around which is wound, the antenna wire 87, the desired number of turns. The frame is also provided with a pivot 88 which fits into a socket bearing 88^a in the panel or motor board 92, permitting 20 the antenna as a unit to swing freely through the openings 93 and 94 provided in the panel or motor board and around the motor compartment 95 and the sound amplifier 65 and 66.

25 The motor for the support shaft 7^a is mounted in the compartment 95 which may be arranged in any convenient position beneath the panel 92 within the chamber 55.

30 The yoke 68, on which is mounted the portion 66, is provided with two lateral arms 70 which are provided with pivots at the end of each arm which fit into bearings arranged in the ball portion 63 of 66, which permits 35 vertical movement of 4, 65 and their connections, lateral movement being provided by the pivot 69 of 68, which fits into the pivot bearing 69^a, and the support 68 is mounted in a well known manner in the chamber 55.

40 The ball portion 63 of 66 is arranged to work in a socket bearing 64 secured to the panel 92.

45 The cover 60 is provided with a resonant chamber 61 formed by a partition 61^a within which may be arranged the elements of a radio circuit including an antenna, which may be conveniently operated when the cover is raised.

50 Sound waves that are projected from the mechanical or electrical reproducer into the chamber 62 formed by the cover when closed will pass through the openings 93 and 94 into the chamber 55 comingling with the sound delivered from 65.

55 The antenna may be removed as a unit by raising the motor board 92 in a well known manner, removing the turntable 7 and lifting the antenna through the top.

60 Arranged within the cabinet in a manner not to interfere with its resonance is a radio telephone receiving circuit, the diagram of which is shown in Fig. 2.

65 This hook up may be modified according to desire for either transmission or reception or substituted for any other well known receiving or transmitting circuit. It may be

built up of a number of separate units comprising separate stages of radio and audio amplification, and a separate tuning and detector unit which may be arranged to meet the different requirements. The hook up 70 may include a battery as a source of energy or may be directly connected to the electric light circuit with proper means to make it suitable for the purpose.

75 In this diagram there is only one adjustment required to tune the set to the proper wave length. This adjustment is accomplished by means of a variable condenser across the loop antenna and given a variation sufficient to tune in any of the radio-phone broadcasting stations that may be heard.

80 J An ordinary switch S controls the current of all the filament of the vacuum tubes used in the radio amplifier, as well as in the field of the loud talkers, which may be of any well known type. Consequently, once the condenser has been adjusted to receive the transmission from a radio broadcasting station with maximum intensity, it is merely 85 necessary to turn on the switch when the station is broadcasting or transmitting, to bring in speech and the music that is being transmitted. This feature makes it a very easily operated radio circuit.

85 In the radio amplifier are incorporated two stages of radio frequency amplification, which may be increased if desired, and three stages of audio frequency amplification so as to operate the loud talkers with maximum 100 efficiency. In this diagram J' represents a single circuit jack, for the connection of the loop-aerial to the set which is made by the means of a plug. J'' are double circuit jacks to cut in the several steps of audio frequency 105 amplification if it is desired to use the transmitter 162, or to plug in a pair of telephone receivers for long distance reception. K' is a variable condenser shunting the loop aerial for the purpose of tuning the circuit to the proper wave-length, while L is the grid leak and K' the grid condenser, the capacity of which depends upon the type of vacuum 110 tube detector used; it is generally between .00025 and .0005 microfarad. T' represents the radio frequency transformers, and T'' the audio frequency transformers. V' represents the vacuum tubes of the radio frequency amplifier. V'' is the detector tube. V''' the amplifying tubes of any make and V'''' the 5 watt power tube upon the plate of which a very high voltage may be applied. R' and R'' are respectively the rheostats of the radio and audio amplifying tubes and R''' the detector tube. A represents the A 115 battery which should be of sufficient size to supply all of the tubes and the field of the loud talkers for sufficient length of time without recharging. C and C' are the grid batteries used on the plates of the last three 120

125

tubes. B is the "B" battery which for maximum efficiency should have a voltage of 200 to 300 volts with the taps for the detector, the radio amplifier and the two first audio amplifier tubes. The grid leaks shown across the secondary windings of the audio frequency transformers are necessary only if a high voltage is used. The radio frequency transformers may be of the iron core type and should be so designed as to cover the band of wave lengths it is desired to receive. If desired they may be of the air type and tuned with variable condensers, and a potentiometer P should be used so as to control the oscillations of the two tubes.

10 The loud speakers 165, 166, 168 and 162 when used as a loud speaker may be connected in series or series parallel and increased to any desired number, not shown in the diagram, should be connected between the plate of the last tube, and the positive of the "B" battery the field coil being in parallel with the filaments of the tubes. The loud speaker 168 is shown mounted on the heavy 20 non-vibratory portion 66 communicating with the passage which leads to 65 or 4. If it is desired, it may be placed on 4 or either of the small tubes and wired as desired.

Thus it is seen that I have provided a 30 device which besides being operable as an ordinary phonograph or a radio receiving set can also be operated in any of the following manners:—

(a) To transmit radio and audible sound 35 impulses from a sound record. To do so the impulses may be first produced by operative contact of the reproducer 5 with the record 6 and discharged into the sound passages 164 and 164^a to the transmitter 162. A variation consists in bringing the transmitter 40 162 in direct contact with the record, in which case the groove variations in the record are translated into electric impulses which are broadcasted through the radio set, and audible sound waves which are amplified and delivered through the amplifying 45 passages of the cabinet.

(b) To broadcast radio impulses while recording sound waves upon a record tablet 50 for possible future reproduction and broadcasting. In this mode of operation, the sound waves of the concert to be broadcasted are phonographically recorded in the usual manner by means of the reproducer 5. The 55 sound waves, while actuating the reproducer to make the record, pass through the sound passages of the cabinet to the transmitter 162 where they are translated into ultra-audio impulses to be broadcasted by the 60 radio set.

(c) To record a radio program on a record tablet while the concert is being listened to. The doors of the cabinet are adjusted to permit the delivery of the sound from the amplifying chamber 55 and the recorder 5 is

placed in contact with a rotating record blank 6 placed on the turntable 7. The impulses are translated into sound by the electromagnetic reproducer 168 and the sound waves are delivered to the mechanical recorder 5 to be recorded on the record and to the audience through the wide end of the horn.

(d) To play a radio selection and a phonographic record of the same selection simultaneously, so that in case the radio fades out the dancing may be continued without interruption.

The subject matter of this application has been carved out of a parent application 80 Serial Number 570,906 filed June 26, 1922. Reference is also made to the following applications, all of which have been carved out of the same parent case:—

Application Serial No. 169,306, filed Feb. 85 18, 1927.

Application Serial No. 308,793, filed Oct. 2, 1928.

Application Serial No. 23,569, filed April 16, 1925.

Each one of these cases including the parent case has been drawn to cover a divisible feature of my invention.

What I claim is as follows:—

1. In a radio set, a stationary frame, a 95 coil pivoted within said frame and means for mounting a plurality of pieces of apparatus within the figure generated by the revolution of said coil.

2. In a radio set, a stationary frame, a 100 loud speaker horn secured to one side of said frame and extending therewithin, and a loop aerial pivotally mounted within said frame and adapted to be revolved about said horn.

3. In a radio set, a stationary cabinet, a 105 loop aerial pivotally mounted within said cabinet, and means supported from said cabinet for mounting a plurality of pieces of radio apparatus within the figure generated by the revolution of said aerial within said cabinet.

4. In a radio set, a stationary cabinet having a pivot member supported from one of its sides, a loop aerial mounted within said cabinet having a cooperating pivot member pivotally engaging said first mentioned pivot member and apparatus mounting means secured to said first mentioned pivot member and disposed within the figure generated by the revolution of said aerial.

5. In a radio set, a stationary frame, radio pickup means positioned in said frame and a loud speaker pivoted to said frame and movable with respect to said frame and said pickup means.

6. In a radio set, a stationary frame, a coil pivoted to said frame, a loud speaker horn pivoted to said frame, each of which are movable with respect to each other and to 130

the frame and means for mounting a plurality of apparatus within said frame.

7. In a radio set, a stationary cabinet provided with a sound outlet opening, a loop aerial pivotally mounted for normal movement within said cabinet and movable with respect to said opening, a loud speaker pivotally mounted within said cabinet and movable with respect to said aerial and means for supporting a plurality of radio
